MEASURING TOOL FOR CARPENTRY AND THE LIKE

Wojciech Stanley Gutowski, Southington, Frank Joseph Kuchta, New Britain, and Robert Ferguson West, Simsbury, Conn., assignors to The Stanley Works, New Britain, Conn., a corporation of Connecticut

Filed Nov. 7, 1967, Ser. No. 9,304

Term of patent 14 years

Int. Cl. D8—02; D10—08

U.S. Cl. D52—6

FIG. 1

FIG. 2

FIG. 3

FIG. 4

FIG. 5

FIG. 6

FIGURE 1 is a perspective view of a measuring tool for carpentry and the like embodying the present invention;

FIGURE 2 is a side elevational view thereof;

FIGURE 3 is a plan view thereof;

FIGURE 4 is a side elevational view of the side opposite that shown in FIGURE 2;

FIGURE 5 is an end elevational view looking from the right of FIGURE 2; and

FIGURE 6 is an elevational view of the opposite end.

We claim:

The ornamental design for a measuring tool for carpentry and the like, as shown.
